DESIGN FOR A TOY FIGURE

Marshall W. Cox, Stow, Mass.

Application April 29, 1940, Serial No. 92,024

Term of patent 14 years

To all whom it may concern:

Be it known that I, Marshall W. Cox, a citizen of the United States, residing at Stow, in the county of Middlesex and Commonwealth of Massachusetts, have invented a new, original, and ornamental Design for a Toy Figure, of which the following is a specification, reference being had to the accompanying drawing, forming a part thereof.

I claim:

The ornamental design for a toy figure, as shown.

MARSHALL W. COX.
